GROUND TOBACCO COMPOSITION

PRIORITY CLAIM

The present application is a National Phase entry of PCT Application No. PCT/EP2018/062116, filed May 9, 2018, which claims priority from GB Patent Application No. 1707758.7, filed May 15, 2017, which is hereby fully incorporated herein by reference.

TECHNICAL FIELD

The present invention relates to a ground tobacco composition which is particularly useful in the preparation of a tobacco extract, and methods of making the ground tobacco composition. The invention also provides a tobacco extract formed from the ground tobacco composition, cartridges containing the tobacco extract for use in a smoking article, and smoking articles comprising the tobacco extract.

BACKGROUND

Tobacco material is heated in smoking articles for the purpose of releasing substances contained in the material and delivering these as an aerosol.

Smoking articles such as cigarettes, cigars and the like burn tobacco during use to create tobacco smoke. Attempts have been made to provide alternatives to these articles that burn tobacco by creating products that release compounds without burning. Examples of such products are heating devices which release compounds by heating, but not burning, material. The material may be, for example, tobacco or other non-tobacco products, which may or may not contain nicotine.

Electronic cigarettes or "e-cigarettes" are another product that has been formulated as an alternative to combustible products. These devices contain a volatilizable solution which generates an inhalable aerosol on heating. These solutions may contain components of tobacco. It is therefore useful to be able to selectively extract tobacco components.

SUMMARY

According to a first aspect of the present invention, there is provided a ground tobacco composition, wherein at least 90% by weight of the tobacco in the composition has a particle size in the range of about 200 μm to about 5 mm.

When extracting components from tobacco, the particle size of the tobacco determines the distance that the tobacco components must diffuse within the tobacco leaf matrix in order to be extracted. Reduction of diffusional resistance by breaking tobacco leaf into small particles increases the rate of leaching of tobacco constituents out of the tobacco. Furthermore, this increases the tobacco surface area thereby increasing contact between the tobacco and extraction solvent.

The inventors have also found that through using a finely ground tobacco, the distribution of tobacco components through the ground tobacco is more consistent and any resulting extract composition has improved consistency, as compared to tobacco extracts obtained from ground tobacco with a larger particle sizes.

On the other hand, extraction solvents flow through a bed of ground tobacco during the extraction process. The separation between particles is greater for larger particles, allowing improved solvent flow and consequently more efficient extraction. Moreover, a narrow particle size distribution

2

improves solvent flow; a wider range of particle sizes can result in a tobacco bed in which small tobacco particles fill spaces between larger particles thereby blocking solvent flow.

5 Further, very fine particles are more likely to be carried in a solvent flow during extraction, contaminating the tobacco extract and/or soiling the extraction equipment.

Balancing these various considerations, the inventors have optimized the particle size and particle size distribution 10 for ground tobacco which is to be subjected to one or more extraction processes.

In some cases, at least 90% by weight of the tobacco in the composition has a particle size in the range of about 355 μm to about 3.5 mm.

15 The inventors have found that the concentration of benzo[a]pyrene and the concentration of metals is higher in tobacco particles having a size of less than 355 μm than in particles having a size of 355 μm or more. As a result of removing tobacco particles having a size of less than 355

20 μm , the extract obtained by extraction from this ground tobacco composition, depending on the extraction solvent, typically contains less metal and/or benzo[a]pyrene than tobacco extracts obtained from previously known ground tobacco compositions.

25 In some cases, at least 95% by weight of the tobacco in the composition has a particle size in the specified range, suitably at least 97% by weight.

According to a second aspect of the invention, there is provided a method of preparing a ground tobacco composition 30 as described herein, the method comprising:

(a) grinding tobacco; (b) removing tobacco particles that are larger than the particle size range using a first sieve; and (c) removing tobacco particles that are smaller than the particle size range using a second sieve.

35 According to a third aspect of the invention, there is provided a tobacco extract obtainable by extracting tobacco components from the ground tobacco composition described herein.

40 A fourth aspect of the invention provides a method of preparing a tobacco extract, the method comprising contacting a solvent with the ground tobacco composition described herein. In some cases, the method of preparing a tobacco extract comprises (a) grinding tobacco; (b) removing tobacco particles that are larger than the particle size range using a first sieve; (c) removing tobacco particles that are smaller than the particle size range using a second sieve; and (d) contacting the ground tobacco with an extraction solvent.

45 A fifth aspect of the invention provides a cartridge configured for use in a smoking article, the cartridge containing a tobacco extract according to the third aspect of the invention. A further aspect of the invention provides a smoking article containing a tobacco extract according to the third aspect of the invention or a cartridge according to the fifth aspect of the invention.

50 55 Further features and advantages of the invention will become apparent from the following description of preferred embodiments of the invention, given by way of example only.

60

DETAILED DESCRIPTION

The invention provides a ground tobacco composition, wherein at least 90% by weight of the tobacco in the composition has a particle size in the range of about 200 μm to about 5 mm. In some cases, at least 90% by weight of the tobacco in the composition as a particle size that exceeds about 250 μm , 300 μm , 330 μm or 355 μm . In some cases,

at least 90% by weight of the tobacco in the composition has a particle size that is less than about 4.5 mm, 4 mm or 3.5 mm. For instance, in some cases at least 90% by weight of the tobacco in the composition has a particle size in the range of about 300 μm to about 4 mm, suitably from about 355 μm to about 3.5 mm.

As used herein, reference to a lower particle size limit means that the tobacco particles will not pass through a sieve with a mesh size of that lower limit. For instance, restriction of the particle size to be greater than 200 μm means that the particles are retained on a sieve with a 200 μm mesh. Similarly, restriction of the particle size to be greater than 355 μm means that the particles are retained on a sieve with a 355 μm mesh.

As used herein, reference to an upper particle size limit means that the tobacco particles will pass through a sieve with a mesh size of that upper limit. For instance, restriction of the particle size to be less than 5 mm means that the particles are not retained on a sieve with a 5 mm mesh (i.e. they pass through a 5 mm mesh sieve). Similarly, restriction of the particle size to be less than 3.5 mm means that the particles are not retained on a sieve with a 3.5 mm mesh (i.e. they pass through a 3.5 mm mesh sieve).

In some cases at least 95% by weight of the tobacco in the composition has a particle size in the specified range, and suitably at least 97%, 98%, 99% or 99.5% by weight of the tobacco in the composition has a particle size in the specified range. In some cases, substantially all of the tobacco in the composition has a particle size in the specified range. In some cases, 100% by weight of the tobacco in the composition has a particle size in the specified range.

The ground tobacco composition is particularly suitable for use in the preparation of a tobacco extract. Any suitable extraction solvent may be used. In some cases, the extraction solvent may be an aerosol generating agent, so that the tobacco components are dissolved and retained in the aerosol generating agent. A tobacco extract formed using an aerosol generating agent as a solvent can be incorporated directly into an electronic cigarette or the like (or a cartridge configured for use with an electronic cigarette). In other cases, the extraction solvent may be, for example, a supercritical fluid, such as supercritical carbon dioxide. Where the extraction solvent is not an aerosol generating agent, the method of preparing a tobacco extract according to the invention may include a solvent switch in which the dissolved tobacco components are transferred from the extraction solvent to an aerosol generating agent. As used herein, an "aerosol generating agent" is an agent that promotes the generation of an aerosol on heating. An aerosol generating agent may promote the generation of an aerosol by promoting an initial vaporization and/or the condensation of a gas to an inhalable solid and/or liquid aerosol.

In general, suitable aerosol generating agents include, but are not limited to: a polyol such as sorbitol, glycerol, and glycols like propylene glycol or triethylene glycol; a non-polyol such as monohydric alcohols, high boiling point hydrocarbons, acids such as lactic acid, glycerol derivatives, esters such as diacetin, triacetin, triethylene glycol diacetate, triethyl citrate or myristates including ethyl myristate and isopropyl myristate and aliphatic carboxylic acid esters such as methyl stearate, dimethyl dodecanedioate and dimethyl tetradecanedioate. In some cases, the aerosol generating agent comprises one or more of glycerol, propylene glycol, triacetin and isopropyl myristate, suitably glycerol and/or propylene glycol.

EXAMPLE

The tobacco moisture content should be in the range of 0-30% by weight, ideally 12-16% by weight. Tobacco was fed into a ball mill type grinder, Urschel Comitrol 3600 with a 3 mm round cutting head.

The particles were then sieved to select particles of the desired size. The ground tobacco was then separated using 10 two sieves; a first, upper sieve with a 3.5 mm mesh size and a second, lower sieve with a 0.355 mm mesh size.

Tobacco particles retained on the top sieve can be retained 15 and returned to the grinder later.

Tobacco particles retained on the lower sieve were 20 retained as the sample for extraction.

Tobacco particles passing through both sieves were 25 discarded. The equipment used for sieving is a Russell Finex 17300 sieve.

Comparison of the starting tobacco material (pre-grinding) with the tobacco particles of sample for extraction shows there is no loss of nicotine or water during the processing steps. Further, the metal content of the starting tobacco material and the tobacco particles of Sample A is the comparable; there is not metal leaching from the processing apparatus into the tobacco.

Moreover, samples taken from different parts of a tobacco leaf were determined to have significant variations in the 30 relative concentrations of various tobacco components. The ground tobacco of the sample for extraction was found to have reduced variation in the concentration of these components as compared to the tobacco leaf.

Chemical and Physical Analysis

Various tests were completed using Virginia tobacco and, 35 separately, Burley Tobacco. The tests were completed following grinding and the various size bands were selected using appropriate sieves. The data are shown below.

a) Chemical Composition.

It can be seen from Tables 1 and 2 below that the concentration of benzo[a]pyrene and toxic heavy metals is highest in tobacco extracts obtained using tobacco particles 40 that are smaller than 355 μm .

TABLE 1

Leaf Type	Particle size	Benzo[a]pyrene in extract (ng/g)
Virginia	200-355 μm	116
	355-710 μm	100
	710-1400 μm	89.8
	>1400 μm	90.8
	All sizes	93.4
Burley	200-355 μm	5.26
	355-710 μm	4.06
	710-1400 μm	3.79
	>1400 μm	3.79
	All sizes	4.02

TABLE 2

Leaf Type	Particle size	Concentration in extract (ng/g)						
		Cd	Pb	Cr	Ni	As	Se	Hg
Virginia	200-355 μm	962	870	1932	951	350	52.4	22.3
	355-710 μm	786	238	402	369	70.4	41.7	18.6
	710-1400 μm	788	262	329	345	58.7	42.1	17.8
	>1400 μm	723	255	441	402	60	38	15.3
	All sizes	747	244	411	373	80.4	42.6	16.1
Burley	200-355 μm	196	673	4001	1993	158	23.2	16.2
	355-710 μm	220	156	646	868	38.4	32.4	16.9
	710-1400 μm	198	159	542	799	37.8	29.2	14.8
	>1400 μm	219	206	602	897	37.0	32.3	14.1
	All sizes	206	269	1104	1018	73	32.5	15.4

15

It can be seen from Table 3 below that the nicotine and moisture content was approximately equal for tobacco extracts obtained from all particle sizes.

TABLE 3

Leaf Type	Particle size	Nicotine (mg/mL)	Water (wt %)
Virginia	200-355 μm	27.6	12.1
	355-800 μm	31.0	13.2
	800-2000 μm	31.6	13.6
	>2000 μm	32.9	14.0
	All sizes	33.3	13.7
Burley	125-355 μm	26.8	10.0
	355-710 μm	31.4	12.2
	710-1400 μm	31.7	12.7
	>1400 μm	30.2	12.9
	All sizes	31.9	12.3

Tobacco extracts were formed by contacting tobacco particles with a 50:50 (w/w) mixture of glycerol and propylene glycol at 100° C. for 15 minutes. (The weight ratio of tobacco to solvent was 1:9). The nicotine concentration in the extracts was approximately the same for all particle size ranges used. The tobacco particle size does not affect the extract nicotine concentration.

b) Size Distribution

The particle size distribution following grinding was measured. The various size bands were selected using appropriate sieves.

Leaf Type	Particle size	Wt %
Virginia	<200 μm	1.3
	200-355 μm	1.4
	355-710 μm	10
	710-1400 μm	29.5
	>1400 μm	57.8
Burley	All sizes	100
	<200 μm	1.4
	200-355 μm	1.8
	355-710 μm	17.4
	710-1400 μm	42.3
	>1400 μm	37.1
	All sizes	100

It can be seen that 2.7wt % of the Virginia tobacco and 3.2wt % of the Burley tobacco had a particle size of less than 355 μm .

15
The various embodiments described herein are presented only to assist in understanding and teaching the claimed features. These embodiments are provided as a representative sample of embodiments only, and are not exhaustive and/or exclusive. It is to be understood that advantages, 20 embodiments, examples, functions, structures, and/or other aspects described herein are not to be considered limitations on the scope of the invention as defined by the claims or limitations on equivalents to the claims, and that other embodiments may be utilized and modifications may be made without departing from the scope of the claimed 25 invention. Various embodiments of the invention may suitably comprise, consist of, or consist essentially of, appropriate combinations of the disclosed elements, components, 30 features, parts, steps, means, etc., other than those specifically described herein. In addition, this disclosure may include other inventions not presently claimed, but which may be claimed in future.

35 The invention claimed is:

1. A method of preparing a tobacco extract from a ground tobacco composition, wherein at least 90% by weight of the tobacco in the composition has a particle size in the range of about 200 μm to about 5 mm, and wherein the ground 40 tobacco composition is contacted with an extraction solvent comprising an aerosol generating agent selected from the group consisting of glycerol, propylene glycol, triacetin and isopropyl myristate.

2. The method of claim 1, wherein at least 90% by weight 45 of the tobacco in the composition has a particle size in the range of about 355 μm to about 3.5 mm.

3. The method of claim 1, wherein at least 95% by weight 50 of the tobacco has a particle size in the range of about 200 μm to about 5 mm.

4. The method of claim 1, the method comprising the 55 steps of:

(a) grinding tobacco;

(b) removing tobacco particles that are larger than the 60 particle size range using a first sieve; and

(c) removing tobacco particles that are smaller than the 65 particle size range using a second sieve.

5. The method of claim 1, wherein at least 97% by weight 70 of the tobacco has a particle size in the range of about 200 μm to about 5 mm.
